[57] CLAIM

The ornamental design for an earring rack, as shown
and described.

DESCRIPTION

FIG. 1 is a front perspective of an earring rack, showing
my new design;

FIG. 2 is a top plan view thereof;

FIG. 3 is a rear plan view thereof;

FIG. 4 is a side view thereof; and,

FIG. 5 is a bottom plan view thereof.

The broken line disclosure of the earrings is for illustrative
purposes only and does not form any part of the
claimed design.*Fig. 1*
